UNITED STATES PATENT OFFICE.

CORBETT L. QUINN, OF PINK HILL, NORTH CAROLINA, ASSIGNOR OF ONE-FOURTH TO ZENON J. QUINN, ONE-FOURTH TO LEMAN H. QUINN, AND ONE-FOURTH TO JAMES W. QUINN, ALL OF PINK HILL, NORTH CAROLINA.

AXLE-LUBRICATING DEVICE.

1,270,658.

Specification of Letters Patent. Patented June 25, 1918.

Application filed February 6, 1917. Serial No. 146,892.

To all whom it may concern:

Be it known that I, CORBETT L. QUINN, a citizen of the United States, residing at Pink Hill, in the county of Lenoir and State of North Carolina, have invented certain new and useful Improvements in Axle-Lubricating Devices; and I do hereby declare the following to be a full, clear, and exact description of the invention, such as will enable others skilled in the art to which it appertains to make and use the same.

This invention relates to an axle lubricating device and has for one of its objects the provision of a device of this character, which may be readily attached to an ordinary carriage wheel for the purpose of lubricating the axle on which the wheel is journaled.

Another object of this invention is to provide a receptacle carried by the spokes of the wheel and having an outlet pipe connected thereto and which extends through the hub of the wheel for the purpose of dispensing lubricant from the receptacle on to the axle.

A further object of this invention is the provision of a valve located within the bottom of the receptacle and adapted to control the outflow of lubricant therefrom into the pipe which communicates with the axle through the hub of the wheel, whereby the quantity of lubricant upon the axle may be readily regulated as desired.

A still further object of this invention is the provision of an axle lubricating device of the above stated character, which shall be simple, durable and efficient, and which may be manufactured and sold at a comparatively low cost.

With these and other objects in view as will become more apparent as the description proceeds, the invention consists of the novel combination and arrangement of parts as will be hereinafter more fully described and claimed.

For a complete understanding of my invention, reference is to be had to the following description and accompanying drawing, in which:

Figure 1 is a fragmentary side elevation of a vehicle wheel illustrating an axle lubricating device applied thereto and constructed in accordance with my invention,

Fig. 2 is a perspective view of the device detached from the wheel,

55

Fig. 3 is a vertical sectional view illustrating the valve for controlling the flow of the lubricant from the receptacle.

Referring in detail to the drawing, the numeral 1 designates the hub of a wheel, journaled upon an axle 2 and having the usual radial spokes 3. The foregoing description relates to a well known construction of wheel and axle and to which my invention is applied.

A receptacle 4 has its side walls diverging as illustrated at 5 and has formed upon its bottom wall a substantially V-shaped member 6 of solid formation. The solid V-shaped member 6 co-operates with the inwardly diverging side walls 5 of the receptacle 4 to form a V-shaped member in outline of the receptacle and the solid member 6 so that the aforementioned members will readily conform to the contour of the spokes or when positioned between the spokes at the apexes thereof as illustrated in Fig. 1, the receptacle and solid member 6 will snugly fit the sides of the spokes. Pairs of relatively spaced straps 7 are secured to the receptacle and are adapted to engage upon each side of the spokes as illustrated in Fig. 1 and have their ends apertured as illustrated at 8 for receiving suitable bolts in securing the straps to the spokes, thus preventing the receptacle from becoming detached from the wheel.

The solid V-shaped member 6 is provided with a transverse opening 9 adjacent the bottom of the receptacle and has rotatably mounted therein a valve 10 to which a thumb piece 11 is secured. The valve 10 has the usual opening 12 which is adapted to be brought into communication with an opening 13 which communicates interiorly of the receptacle. Communicating with the transverse opening 9 is a passage 14 which is adapted to register with the opening 12 when the valve 10 is properly positioned. A pipe 15 connects with the passage 14 and extends downwardly and through the hub 1 of the wheel to the interior thereof for permitting the contents of the receptacle, when the valve is opened as shown in Fig. 3 to pass through the hub on to the axle.

The upper end of the receptacle 4 is re-

duced to form a filling spout 16, which is externally screw-threaded for receiving a cap 17. A suitable stopper or cork 18 is positioned within the neck or filling spout 16 before the cap is applied thereon to form an airtight receptacle.

In operation, when it is desired to lubricate the axle of the vehicle, the receptacle 4 is filled with lubricants such as oil or the like, and by opening the valve 10 so that the opening 12 thereof communicates with the opening 13 in the passage 14, the lubricants will pass downwardly and outwardly of the receptacle through the hub onto the axle. The amount of lubricant passing on to the axle may be readily regulated by the valve 10 according to how far the valve is moved into an opened position. The receptacle 4 is adapted to be filled with lubricant at all times, and if desired, the valve 10 may be sufficiently opened to permit the lubricant within the receptacle to drip slowly therefrom and which will be sufficient to keep the axle well lubricated during the rotation of the wheel thereon. However, if the axle is supplied with too much lubricant, the valve may be entirely cut off preventing any further lubricant from passing on to the axle.

While I have shown and described the preferred embodiment of my invention, it will

be understood that minor changes in construction, combination and arrangement of parts may be made without departing from the spirit and scope of the invention as claimed.

35

Having thus described my invention, what I claim is:

An axle lubricating device comprising a substantially V-shaped receptacle adapted to be disposed between the spokes of a wheel 40 permitting the apex thereof to rest against the hub, said apex portion being of solid formation and having a transverse opening and vertical passages in communication therewith, one of said passages connected with the 45 interior of the receptacle and the other passage extending laterally and opening outwardly of the receptacle, a tube connecting the last named passage with the hub, and a valve plug having an opening located in the 50 transverse opening and adapted to be turned to register the opening thereof with the passages, and means securing the receptacle to the spokes.

In testimony whereof I affix my signature 55
in presence of two witnesses.

CORBETT L. QUINN.
